The ornamental design for an instrument panel for automobile, as shown and described.

DESCRIPTION

FIG. 1 is a front, left, top perspective view of an instrument panel for automobile in accordance with our new design, a mirror image thereof is claimed but not shown;

FIG. 2 is a front, right, top perspective view thereof;

FIG. 3 is a front elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken lines illustrate portions of the instrument panel for automobile which form no part of the claimed design.
